UNITED STATES PATENT OFFICE

ALLEN P. BOURDON AND LEO R. BOURDON, OF WOODSTOCK, VERMONT, ASSIGNEES TO
WOODSTOCK MANUFACTURING COMPANY, OF WOODSTOCK, VERMONT, A CORPORA-
TION.

MERRY-GO-ROUND.

1,313,668.

Specification of Letters Patent.

Patented Aug. 19, 1919.

Application filed October 16, 1916. Serial No. 125,930.

To all whom it may concern:

Be it known that we, ALLEN P. BOURDON and LEO R. BOURDON, citizens of the United States, and residents of Woodstock, in the county of Windsor and in the State of Vermont, have invented a certain new and useful Improvement in Merry-Go-Rounds, and do hereby declare that the following is a full, clear, and exact description thereof.

10 The object of our invention, primarily, is to provide in a simple and compact form and in a form, which, while readily portable will possess all required strength and stability, an amusement device of the merry-go-round type, and to this end and to such others as will be appreciated when the nature of the invention and the embodiment thereof are better understood from the hereinafter given description, said invention 15 consists in the apparatus constructed substantially as hereinafter specified and claimed.

In the accompanying drawings—

20 Figure 1 is a perspective view of an apparatus embodying one form of our invention;

Fig. 2 is a vertical section thereof;

Fig. 3 is a perspective view illustrating a different embodiment of our invention.

25 Briefly described our invention comprehends any number of seats for passengers mounted to revolve in a horizontal direction around a vertical axis, and a suitable number of propelling arms, or levers, preferably 30 one for each seat provided so that each person occupying a seat may participate in the work of propulsion.

35 A base 10 is provided, which, as shown, may take the form of intersecting, or crossing bars of sufficient length to afford stability, which are joined, where they intersect, to each other and to a central platform 11, to which is rigidly attached and from which rises vertically a round post 12, 40 which may be a piece of pipe, or tubing. Said post is secured at its bottom to a flanged socket 13 that is secured by screws, or bolts to the platform. Pivotaly mounted upon the post, so as to be rotatable about 45 the same, is a plurality of radial arms, each of which at its outer end supports a seat 14. As shown in Fig. 1 of the drawings, there are two seats and, therefore, two radial arms, and the two arms are formed of a light

frame-work which consists of a pair of parallel horizontal bars 15 which straddle and are secured to the upper portion of a tube, or sleeve 16, which is fitted to rotate upon the post, and braces 17, which are attached to and extend from the lower end of said tube, 50 or sleeve, upward and outward, and at their outer ends are securely fixed to the horizontal frame bars. The braces at thier lower ends are secured to each other and to the sleeve by two plates 18 situated 55 on opposite sides of the sleeve and bolts 19, which pass through the plates and the ends of the braces between them. It will be seen that the braces, by reason of their location, are compression members, 60 they are situated where they are not in the way, and they aid in placing the center of gravity of the apparatus very low, so that while its parts are few, and in themselves light, the structure has abundant strength 65 and stability so that it cannot easily be overturned. By reason of the construction, the frame-work forming the arms can be made of wood. The pair of horizontal bars 15 are bolted to a flange collar 21 which is 70 secured to the upper end of the sleeve. The tube, or sleeve 16 rests at its bottom upon the top of the post socket 13. Thus a strong, light frame work supported by a long bearing upon the central post which affords 75 ample rigidity to the structure, is provided. At the top of the post at a height about the plane, or level of the out-stretched arms of the occupants of the seats, is rigidly fixed a wheel 22, preferably a toothed wheel, al- 80 though not necessarily such, and preferably for each car, or seat, a radially extending arm, or lever 23, is pivoted to the post concentric with the wheel, and to each is pivot- 85 ally attached a spring-held pawl 24, which 90 engages the teeth, or periphery of the wheel, so that when the occupant of a seat, or car grasps the outer end of an arm, or lever, which is in a convenient position to reach 95 and pushes the lever forward and then 100 pulls backward upon it, rearward move- 105 ment of the lever will be prevented by en- gagement of the pawl and wheel, and thus the occupant of the seat and the latter will be propelled forward and, of course, with sufficient force to carry forward the operating lever for a repetition of the operation just described, with the result that the seat

- occupant and the seat will be carried around in a circular path about the post, and at considerable speed and without any great tax upon the strength, by reason of the 5 length of the operating lever. The operating arms, or levers, are preferably made of wood and each is pivotally connected with the post, or upright by a pair of metal straps 25 bolted, respectively, to the top and 10 bottom of the arm and reaching over the wheel, and the pivoting ends of the straps of the two arms lap past each other. The dog, or pawl 24 is conveniently pivoted between these straps.
- 15 With the seats, or cars connected together in pairs, as shown in Fig. 1, each occupant of a seat contributes to the propulsion of both seats, or if desired, the propelling movement may be performed by one person.
- 20 In the form of our invention shown in Fig. 3, instead of connecting diametrically opposite seats rigidly together in pairs that rotate together, the seats are mounted independently upon the stationary post, so that 25 there can be relative movement of the seats in the circular path in order to introduce the element of racing. In this case, of course, for each seat there is provided its own operating lever and preferably means 30 are provided to prevent collision of one seat with another, which means may take the form of a stop projection 26, attached to each seat supporting arm 150, and located preferably near the pivotal post, which, by 35 contact with the preceding seat arm will prevent the coming together of the seats. In this case the braces 170 are independent of each other and each has at its inner post-engaging end its own eye 171 connecting it 40 with the post 12.

In constructing the apparatus for use of children, each seat, at least on its outer side, as is common in merry-go-rounds, may be given the form of a horse, or other animal, 45 or other object which would be attractive, or appeal to children.

As preferably constructed, certain of the arms of the base 10 have a hinged, or pivoted connection with the platform 11, so 50 that they may be folded up for convenience in storing and shipping. Thus, as shown in the drawings, where four bars, or legs are employed, two opposite ones may consist of a continuous piece rigidly, or fixedly secured to the platform 11, while each of the 55 other two is hinged by bolts, or screws 27 at

diagonally opposite corners of the base, and at the inner end of each is a tenon 28 adapted to enter a mortise 29 in the rigid leg when the hinged leg is swung into position for use. 60

Of course, we do not limit ourselves to any particular form of seat, or passenger support, as the same may have any of the forms common in merry-go-rounds, or any desired form. 65

It will be evident that our apparatus, while primarily intended as an amusement device for children, may, nevertheless, be given a form suiting it for adults for exercise purposes. 70

Having thus described our invention what we claim is—

1. In a device of the class described, the combination of a supporting base, a post rising therefrom, a plurality of seats, an 75 arm for each seat radiating from the post, said arms being capable of independent rotary movement, a sleeve to which the arm is attached mounted to revolve about the post, a wheel fixed stationarily to the post 80 above the arms, and propelling means comprising an arm pivoted to the post and radiating therefrom to the seat, and a pawl carried by said arm.

2. In a device of the class described, the 85 combination of a supporting base, a plurality of seats mounted for independent rotation horizontally about a common vertical axis, and means for propelling a seat independently of adjacent seats in the rotation 90 thereof about said common axis, whereby the distance apart of the seats may vary in their movement around such axis.

3. In a device of the class described, the combination of a supporting base comprising 95 a platform, and legs extending outwardly therefrom, certain of which are pivotally connected with the base to swing horizontally, a post rising therefrom, a plurality of seats, an independent arm for each seat 100 radiating from the post, a sleeve to which the arm is attached mounted to revolve about the post, a wheel fixed stationarily to the post above the arms, and propelling means comprising an arm pivoted to the post and 105 radiating therefrom to the seat, and a pawl carried by said arm.

In testimony that we claim the foregoing we have hereunto set our hands.

ALLEN P. BOURDON.
LEO R. BOURDON.
